[57] **ABSTRACT**

For initial threading of a coil of metal through a rolling mill the settings of the mill are modified, in accordance with calculated and measured data, to minimize the amount of distortion on the nose of the coil of metal. The settings of the mill are then returned to a nominal schedule for rolling the rest of the coil.

METHODS OF ROLLING STRIP MATERIALS, AND STRIP MATERIALS ROLLED THEREBY

This invention relates to methods of rolling strip material, and more particularly but not exclusively, to rolling of metal strip, such as steel strip, and also to strip material rolled by these methods.

It is well known that in the rolling of steel strip, particularly broad thin strip, care must be exercised to avoid what is known as "bad shape". "Shape" refers to the transverse cross-section of the strip i.e. transverse gauge profile, and transverse variation in the longitudinal tension/stress pattern of the strip. Excessive stress differences across the strip can cause buckling of the strip, i.e. "manifest bad shape". If the strip is subjected to sufficient longitudinal tension, buckling may be avoided but the potential for buckling is not necessarily eliminated, in which case the strip has "latent bad shape", and may buckle for example when cut into narrower strips.

When threading strip into a mill, particularly a multi-stand tandem mill, for subsequent rolling to reduce gauge, the shape of the nose i.e. the first few feet of the strip can give rise to great difficulties of threading, particularly as tension cannot be applied to obviate manifest bad shape. In some cases, bad nose shape may prevent the nose entering a stand (or automatic threading devices for a stand, where employed). The operator then has to stop the mill, cut off the bad nose, and reattempt threading. This results in undesirable scrap, and loss of mill utilisation time.

It is therefore an object of the invention to provide a method of rolling strip materials which obviates or mitigates the above difficulties of threading.

According to one aspect of the invention a method of rolling strip material in a rolling mill having at least one adjustable rolling stand, comprises the steps of:

a. from measurements of the mill settings and data regarding the strip material to be rolled, calculating at least approximately the roll force to give the required gauge which should theoretically occur on the nose of the strip material at each stand, and also calculating theoretically the roll camber at each stand;

b. determining at least approximately the ideal roll force for each stand which, with the calculated roll camber on the respective stand, will give the nose a shape threadable into a subsequent rolling stand or a shape within predetermined limits of badness;

c. comparing the calculated roll force at each stand with the determined ideal roll force at that respective stand, and if the calculated roll force differs from the determined ideal roll force sufficiently to give the nose an unthreadable shape or a shape outside predetermined limits of badness, modifying the mill settings to produce a roll force and/or a roll camber for each stand which will give the nose a threadable shape or a shape within predetermined limits of badness;

d. threading the strip material through the mill and as each inner-stand tension is successively established, changing the settings of the mill to those settings appropriate to a predetermined rolling schedule (if not already at those settings); and

e. rolling the strip material substantially according to the rolling schedule. There is also provided:

A rolling mill having at least one adjustable rolling stand, including

a. means for sequentially measuring the mill settings and data regarding the strip material to be rolled, means for calculating at least approximately the roll force to give the required gauge which should theoretically occur on the nose of the strip material at each stand, and also means for calculating theoretically the roll camber at each stand;

b. means for determining at least approximately the ideal roll force for each stand which, with the calculated roll camber on the respective stand, will give the nose a shape threadable into a subsequent rolling stand or a shape within predetermined limits of badness;

c. means for comparing the calculated roll force at each stand with the determined ideal roll force at that respective stand, and if the calculated roll force differs from the determined ideal roll force sufficiently to give the nose an unthreadable shape or a shape outside predetermined limits of badness, means for modifying the mill settings to produce a roll force and/or a roll camber for each stand which will give the nose a threadable shape or a shape within predetermined limits of badness;

d. means for threading the strip material through the mill and as each inter-stand tension is successively established, changing the settings of the mill to those settings appropriate to a predetermined rolling schedule (if not already at those settings); and

e. means for rolling the strip material substantially according to the rolling schedule.

30 Interstand-tension includes the tension between the final stand and the reel.

The mill settings which may be modified in step (c) may be roll gap, and alternatively or additionally in the case where there is provision for varying roll camber, (for example by roll-bending jacks), roll camber.

35 The roll camber calculation of step (a) may be based on a knowledge of camber built-in to the rolls of the rolling stand in question, for example by grinding during their manufacture and roll wear during use, together with a knowledge of thermal dissipation in the rolls during working and idling periods which when applied to a mathematical model of the dynamic thermal camber of the rolls, gives the instantaneous thermal camber.

40 The aforesaid calculations may be performed in a computer, preferably a suitably programmed digital computer.

Another aspect of the present invention comprises 50 strip material when rolled by the above method. In a preferred embodiment said rolled strip material may be for example steel or aluminium.

55 Embodiments of the invention will now be described by way of example, with reference to the problems of threading a coil of steel strip into a multi-stand cold rolling tandem mill and with reference to FIGS. 1 and 2 of the drawings.

The resultant shape of the coil nose after threading 60 through a roll stand is dependent on how close is the roll force which occurs in rolling the nose compared with the roll force which will deform the work rolls (by bending and flattening) so as to compensate for the total camber (ground and thermal) existing on the rolls. If compensation is correct then the shape of the rolls will exactly match the incoming transverse gauge profile of the strip and perfect exit shape results. If compensation is not exact then the shape of the rolls, as the nose is being rolled, will not match the incoming

transverse gauge profile and various degrees of bad shape occur. There are two possibilities — alter the total crown of the rolls by some additional means of roll bending e.g. jacks — or alter the roll force which will occur during rolling of the nose. For a stand without roll bending jacks there is only the latter possibility.

The description now refers, by way of example to a four-stand tandem mill with roll bending jacks on the first and last stand.

The steps involved in the method for ensuring good shape on the nose are as follows:

a. The roll force which will theoretically occur on the nose i.e. the front first few feet of the strip is calculated using known models giving roll force F_T^i as a function of inter-stand thickness during threading of the strip, inter-stand tensions, yield stress of the strip and roll gap friction.

Such a model gives the following dependence $F_T^i = Wf(h_T^i, T^i, K^i, \mu^i)$ for stand i where

F_T^i = total roll force

W = width of strip being rolled

h_T^i = threading gauges on thickness of strip

T^i = inter-stand tension

K^i = Yield stress of the strip

μ^i = friction in roll gap at stand i

f indicates that F_T^i is a function of the above variables.

The roll camber is also calculated as follows:

The ground camber is known for each stand from the dimensions of the rolls. The thermal camber, to be added to the effect of the ground camber is then calculated as follows:

Firstly when pre-calculating the set up for a coil a coefficient of thermal camber per unit speed C_i is calculated for each stand. The equation for this is based on the proportion of the losses in each roll gap that flow into the rolls. This causes differential thermal expansion and changes in the camber of the rolls.

The thermal camber coefficient for stand i is calculated assuming that the rolls had settled down to steady state conditions i.e. as if the coil had been rolled at one per unit speed for an infinite time.

The formula for C_i is as follows:

$$C_i = \frac{Ce}{Hrc} \left[\frac{Tc^i}{W} + h^i R^i (\sigma^i - \sigma^{i-1} - Ec)(1+f^i) \right]$$

where

Ce = Coefficient of thermal expansion of work rolls

Hrc = Heat transfer coefficient from roll to coolant

Tc^i = calculated roll torque

W = strip width

h^i = exit thickness from stand i

R^i = work roll radius stand i

σ^i = exit tension stress from stand i

f = forward slip at stand i

and where Ec is given by:

$$Ec = K^{i-1} \left[\ln(1-r^{i-1}) + \frac{r^{i-1}}{5} \right] - K^i \left[\ln(1-r^i) + \frac{r^i}{5} \right]$$

where

K^i = exit yield stress from stand i

r^i = reduction from thickness at the exit stand i i.e. the amount of reduction of thickness from mill entry to the exit of stand i .

Secondly estimates of thermal camber $C^i(t)$ are calculated every 15 secs as follows:

1. A single measurement of the stand speed ω_i is taken for each of the stands.
2. The "steady state" camber at time t is calculated as

10

$$C_{\infty}^{oi}(t) = \omega_i C^i \quad i = 1, 2, 3, 4$$

15

Where C^i is the steady state camber/unit speed as calculated above and $C_{\infty}^{oi}(t)$ is the thermal camber that would be reached running at speed ω_i for an infinite time.

20

3. The actual Thermal camber $C_{\infty}^i(t)$ at time t is therefore given by: $C_{\infty}^i(t) = 1, C_{\infty}^{oi}(t) + 1_2 C_{\infty}^{oi}(t-\Delta t) + 1_3 C_{\infty}^{oi}(t-2\Delta t) + 1_4 C_{\infty}^{oi}(t-3\Delta t) + 1_5 C_{\infty}^{oi}(t-4\Delta t) + 1_6 C_{\infty}^{oi}(t-5\Delta t)$

25

4. All values of C_{∞}^i and C_{∞}^{oi} are updated by shifting one value in time every 15 secs.

30

Thus $C_{\infty}^i(t)$ is calculated from present and previous values of the steady state camber e.g. $C_{\infty}^{oi}(t)$ and from previous values of the actual thermal camber i.e. $C_{\infty}^i(t-\Delta t)$ where Δt = the sampling interval of 15 secs, and $1_1, 1_2, \dots, 1_6$ are constants.

35

b. Having now obtained the calculated roll camber the ideal roll force can be calculated as follows:

35

The zero shape roll force per unit strip width is given by:

40

$$S^i = +f_1 + f_2 \left[f_3 + f_4 GC^i + f_5 (f_6 C_{\infty}^i - \frac{h^i}{h^0} (f_7 + f_8 h^0)) \right] \frac{Wf}{W} \left[\frac{f_9}{f_{10} W} \right]^2$$

45

C_{∞}^i is the work roll camber estimate, f_i etc are constants, GC^i is the ground camber at st and i ; Wf is the roll face width. h^0 is the entry gauge to the mill. The ideal roll forces are thus given by $F_o^i = S^i W$ (W = strip width)

50

c. The tolerances F_L^i on ideal shape is $F_L^i = f_{11}^i (1 + f_{12} W + f_{13} h_{i-1})$ $i = 1$ to 4. f_i are constants. The inequality $(F_o^i - F_L^i) \leq F_T^i \leq (F_o^i + F_L^i)$ is tested for stands 1 to 4 in succession.

55

Therefore no changes are made unless this limit is exceeded. If the limit is exceeded then a minimum change F_{li} is made to the roll force at each stand to return to within the required limits. This minimum change then leaves the roll force as near as possible to that which will give the desired gauge and therefore causes a minimum change in gauge.

60

If this limit is exceeded on any of the stands then, defining

65

$$\Delta F_{li} = 0$$

$$\Delta F_{li} = (F_o^i + F_L^i) - F_T^i$$

$$\Delta F_{li} = (F_o^i - F_L^i) - F_T^i$$

$$F_o^i - F_L^i \leq F_T^i \leq F_o^i + F_L^i$$

$$F_T^i > F_o^i + F_L^i$$

$$F_T^i < F_o^i - F_L^i$$

the threading gauge offsets to compensate for bad shape during threading are specified by the equations

$$\Delta h^i = \frac{1}{W h^i} \frac{(dP)}{dh} \left[F_{14} \Delta F_{1i} - M_i h_{i-1} f_{15} \Delta h_{T^{i-1}} \right] \quad i = 1-4$$

There are upper and lower limits to Δh^i as follows:

$$\Delta h^i = f_{16} \text{ if } \Delta h^i < f_{16}$$

$$\Delta h^i = f_{17} \text{ if } \Delta h^i > f_{17}$$

$$\Delta h_T^i = \frac{h_{i-1}}{h_i} f_{15i} \Delta h_{T^{i-1}} + \Delta h_i$$

$\Delta h_T^0 = 0$ (for the first stand i.e. the entry gauge to the mill)

Δh_i = change on stand i for shape only

h^i = exit gauge from stand i

$(dP/dh)_i$ = change of roll force with exit gauge at stand i

$f_{14} - f_{17}$ are constants

ΔF_{1i} is mathematically defined above and is the change in gauge force which will be made to obtain tolerable shape

M_i = mill modulus

h_{i-1} is entry gauge to stand i

$\Delta h_{T^{i-1}}$ = total thread gauge change of previous stand i

Δh_T^i is the total thread gauge change for stand i and is in two parts (i) the change for shape only Δh^i (ii) the effect of $\Delta h_{T^{i-1}}$.

The mill settings for the stands of the mill can then be recalculated from the roll forces $F_T^i + \Delta F_T^i$ and the gauges $h_T^i + h_i \Delta h_T^i$.

The first and last stands have roll bending jacks and the required jack forces J_i (for stand i) are given by

$$J_i = KO_1 \left[KO_2 + F_T^i \left(\frac{KO_3}{W} + KO_4 \right) + KO_5 GC^i + KO_6 \left(\frac{Wf}{W} \right)^2 \left(C_2 + h^i \left(\frac{KO}{h^0} - 7 + KO_8 \right) - \frac{KO_9}{W - KO_{10}} \right) \right]$$

$KO_1 - KO_{10}$ are constants determined by the mill geometry.

These changes are made to the various stands and the mill is then ready to receive the strip.

d. The change of settings (e.g. screw positions for rolls, roll speeds, jack forces) to return to the settings appropriate to a predetermined rolling schedule are accomplished by removing the changes made at each stand in sequence as the strip enters the following stand. This then minimises the amount of off-gauge material produced.

The change of settings is preferably accomplished without disturbing interstand tensions, for example by employing the non-interactive gauge control methods described in "Journal of The Iron and Steel Institute", Volume 209, part 11, November 1971, pages 869 to 875.

Referring now to FIG. 1 which shows the implementation of this invention in a digital computer 22 (see FIG. 2) block 100 is the predetermined rolling schedule (i.e. interstand gauges and tensions. This could, for example, be obtained from punched paper tape or calculated by a computer programme. This schedule is fed

as input to a thread rollforce calculator block 101 in which the rollforce which will theoretically occur on the nose is calculated in accordance with section (a) of the above described method.

5 The nominal schedule from 100 is also fed to a thermal camber calculator 102 which calculates the thermal camber as described in section (a) above to be used by the zero shape rollforce calculator 103 as described in section (b) above.

10 The outputs of 101 and 103 are compared in comparator 104 as described in section (c) above and the output of 104 is used to calculate the jack force settings and gauge changes required for threading as described in section (c) above. The output programme is then 15 used to apply these settings to mill during threading and remove them as described in section (d) above.

FIG. 2 shows a rolling mill with 4 stands 1 to 4, metal strips to be rolled, screws position controllers 5 to 8, speed controllers 9 to 12 and jack force controllers 13, 20 14. The digital computer, 22, as described with reference to FIG. 1, calculates the jack forces J_1, J_4 and thread gauge corrections Δh_T^i which are applied to the controllers through the gain setting amplifiers 15 to 21, and summing amplifiers 23, 24.

Alternatively if the mill is equipped with automatic tension controls using the screwdowns at each stand then this can be used to remove the threading changes as the strip passes through the mill.

30 If the mill has no roll bending jacks then it is difficult to achieve both the correct gauge and shape for the nose of the coil. However with roll bending jacks by adjusting both the roll gap and the jack force it is much easier to obtain both correct gauge and shape.

35 What we claim is:

1. A method of rolling strip material in a rolling mill having at least one adjustable rolling stand, comprises the steps of:

40 a. from measurements of the mill settings and data regarding the strip material to be rolled, calculating at least approximately the roll force to give the required gauge which should theoretically occur on the nose of the strip material at each stand, and also calculating theoretically the roll camber at each stand;

b. determining at least approximately the ideal roll force for each stand which, with the calculated roll camber on the respective stand, will give the nose a shape threadable into a subsequent rolling stand or a shape within predetermined limits of badness;

c. comparing the calculated roll force at each stand with the determined ideal roll force at that respective stand, and if the calculated roll force differs from the determined ideal roll force sufficiently to give the nose an unthreadable shape or a shape outside predetermined limits of badness, modifying the mill settings to produce a roll force and/or a roll camber for each stand which will give the nose a threadable shape or a shape within predetermined limits of badness;

d. threading the strip material through the mill and as each inter-stand tension is successively established, changing the settings of the mill to those settings appropriate to a predetermined rolling schedule (if not already at those settings); and

e. rolling the strip material substantially according to the rolling schedule.

2. A rolling mill having at least one adjustable rolling stand, including

- a. means for sequentially measuring the mill settings and data regarding the strip material to be rolled, means for calculating at least approximately the roll force to give the required gauge which should theoretically occur on the nose of the strip material at each stand, and also means for calculating theoretically the roll camber at each stand; 5
- b. means for determining at least approximately the ideal roll force for each stand which, with the calculated roll camber on the respective stand, will give the nose a shape threadable into a subsequent rolling stand or a shape within predetermined limits of badness; 10
- c. means for comparing the calculated roll force at each stand with the determined ideal roll force at 15

that respective stand, and if the calculated roll force differs from the determined ideal roll force sufficiently to give the nose an unthreadable shape or a shape outside predetermined limits of badness, means for modifying the mill settings to produce a roll force and/or a roll camber for each stand which will give the nose a threadable shape or a shape within predetermined limits of badness;

d. means for threading the strip material through the mill and as each inter-stand tension is successively established, changing the settings of the mill to those settings appropriate to a predetermined rolling schedule (if not already at those settings); and

e. means for rolling the strip material substantially according to the rolling schedule.
